UNITED STATES PATENT OFFICE

THOMAS W. DELANEY, OF ST. PAUL, MINNESOTA

FURNACE CONTROL

Application filed October 12, 1929. Serial No. 399,379.

This invention relates to furnace control for steam boilers.

The invention has for its general object to provide an operating means whereby furnaces under steam boilers may be positively controlled by the rate of flow of steam from the boilers at all loads.

It is also an object of the invention that furnaces for a group of boilers may be operated to permit any one boiler to assume or reject its portion of the total load.

It is also within the scope of the objects of the invention that adjustments may be made whereby one or more boilers in a group may be operated at a fixed load while other boilers in the group serve to absorb fluctuations in the total load.

Other objects relating to details of construction, combination and arrangement of parts will hereinafter appear in the detail description to follow.

The invention is illustrated by way of example in the accompanying drawings, in which:

25 Figure 1 is a schematic view of the control apparatus of this invention for a boiler and its associated furnace,

Figure 2 is a view in elevation and partly in section of the pressure control switch or apparatus and illustrating the manner in which the same is connected to a steam main,

Figure 3 is a horizontal sectional view taken substantially on the line 3—3 of Figure 2,

35 Figure 4 is a plan view of the switch control for the operating motor,

Figures 5, 6 and 7 are cross sectional views taken substantially on the lines 5—5, 6—6 and 7—7 respectively of Figure 4, and

40 Figure 8 is a skeleton view of the pipe connecting assembly.

Referring to the drawings more particularly, 10 is a steam main, 11 a control pressure tank, 12 a pressure control switch or apparatus, 13 a rotary switch and furnace control wheel, and 14 an electric motor for operating said wheel.

As best shown in Figure 2, the unit 12 comprises a tank 15 within which there is positioned a cylinder 16 of insulating material.

The cylinder 16 is supported by its flange 17. The cylinder has embedded therein a large number of current conductors or wires 18. The wires 18 extend longitudinally of the cylinder 16 and are arranged in spaced relation about the entire periphery of the cylinder with the lower end thereof terminating to form a convolution of a spiral. The lower end of each wire is projected to provide an exposed terminal as indicated for example at 19. The upper end portions of the wires are embedded in the flange 17 and extended as shown for facilitating the connection of leads thereto.

Upon the flange 17 there rests a plate 21 which supports a yoke 22. The yoke 22 is formed with a collar 23 within which is rotatable a nut 24 through which is threaded the upper end of a stem 25. The nut 24 is free to turn within the collar 23 but restrained against longitudinal movement upon stem 25. A hand wheel 26 is keyed to the upper end of nut 24. Stem 25 extends through an axial bore provided in cylinder 16, and the lower end of said stem supports a cylindrical tank 27 which surrounds the cylinder 16 as shown, and is made from current insulating material. The rod or stem 25 is further provided with a stop 28 whereby the rod 25 is prevented from turning.

The cylinder 16 is further provided with two chambers or cavities as indicated at 29 and 30, and each chamber communicates with two bores extending the entire length of the cylinder as indicated by the reference characters 31 and 32 respectively. Also, the cylinder has embedded therein a conductor 33 which extends the entire length of the cylinder and has its lower end exposed while its upper end extends through the flange 17, as indicated at 39 in Figure 1.

Two auxiliary tanks 40 and 41 are provided, the tank 40 communicating with chamber 29 through pipe 42 and tank 41 communicating with chamber 30 through pipe 43.

The steam main 10 is provided with an orifice plate of the usual construction as indicated at 44. Assuming the steam flows in the direction of the arrow 45, then there occurs what may be termed a low steam pres-

sure side and a high steam pressure side with respect to the orifice plate 44 in a manner well understood. The bottom of tank 40 is connected through pipe 46 with the high pressure side of steam main 10, while the low pressure side of said main is connected to the lower end of the tank 15 through pipe 47. The lower end of tank 41 is connected to an outlet of the pressure tank 11 through pipe 48. Pipe 46 is connected at the point shown with pipe 50 which in turn is connected with pipes 47 and 48. Pipe 50 is provided with valves 51 and 52. Also pipe 50 communicates with pipe 47 through pipe 53, and pipe 53 is provided with a valve 54. The pipe 50 further communicates in turn with pipe 46 by pipe 55, the pipe 55 including a valve 55^a. The connection between tank 11 and 41 is provided with a valve 48' and the connection between the high pressure side of steam main 10 and lower end of tank 15 is provided with a valve 47'.

Now referring to the furnace control wheel 13, 56 indicates a shaft driven by the motor 14, and 57^a suitable reduction gearing driven by shaft 56 for rotating a shaft 58 which supports the wheel 13. The wheel 13 carries a multiplicity of contacts 59 to which the different conductors 18 are connected as illustrated in Figure 1. An adjustable clamping block 61 is attached to supporting frame of rotary switch by arm 60 whereby disc carrying contact blocks may be manually adjusted and held stationary by clamp. A second arm 62 is carried by shaft 58, said arm preferably being of insulating material and carrying two conductor fingers 63 and 64.

The shaft 58 carries two cams 64' and 65. A guide link is provided for each cam, as indicated at 66 and 67, respectively. Each guide link is provided with a roller, as at 69, which is adapted to ride upon its associated cam. Also, each guide link is pivotally anchored as at 67 on supporting frame 60 thereby causing each link to swing upon its pivot 67 with the rotation of the wheel 13 in either direction. Connecting rods 69^a and 69^b are pivoted on links 66 and 67 at roller axis and translate motion imparted to links by cams into rectilinear motion in direction desired. Opposite ends of rods 69^a and 69^b are connected to control ends of rods which are connected to control apparatus of furnace such as speed control of fuel feed, dampers, motor speed controller, etc.

The switch control for the motor 14 is shown in detail in Figures 4 to 7, inclusive, and comprises two switch units as indicated generally at 60^a and 70^a. Each unit includes an electro-magnet, as at 70' and 71', respectively, and a shaft 71, said shafts being in axial alignment and each carrying three contact-making arms, as indicated at 72, 73 and 74 in each unit. The middle arm 73 in each case serves as an armature for its respective

electro-magnet as illustrated to advantage in Figure 5. The contact arms for unit 69^a are substantially U-shaped, as shown in Figure 5, while the contact arms for unit 69 are straight, as shown in Figure 7. The switch control is housed in a suitable casing 75 which supports the electro-magnet 71' as well as shafts 71. The casing also supports a bracket plate 76 which in turn supports electro-magnet 70' as shown in Figure 5. A compression spring 77 is provided for the outer contact arms 72—74 for each switch unit and arranged as shown in Figures 5 and 7, respectively. It should be noted that the two switch units are interlocked so that one switch in its closed position maintains the other switch in its open position and vice versa. Both switches may be open.

The contact arms 72, 73 and 74 carry suitable contacts 78 which are adapted for engaging stationary contacts 79 carried by the casing 75. The contacts 78 are connected to current supply leads 80 while contacts 79 are connected to the motor supply leads 81. Electro-magnet 70' is connected in series with contact finger 63 and one of the supply leads 79^a through leads 82 and 83, respectively, while electro-magnet 71' is similarly connected to contact finger 64 and one of the supply leads 79^a through leads 84 and 85, respectively. It should be noted that the conductors 18 are connected to the contacts 59 of wheel 13, that the conductor 38 is connected to one of the supply leads 79^a and that contacts 59 correspond in number to the conductors 18. Also, it will be noted that the contacts carried by the arms of the switch unit 70 are connected to the motor leads 81 in reverse order with respect to the switch arm contacts of the switch unit 69.

The shaft 56 carries a brake drum 86 for which there is provided a split brake band 87, one end of which terminates in a lug 88 while its other end terminates in a finger 89. Between the lug 88 and finger 89 there is provided a pivoted sleeve 90 which is formed with a lug 91 and a plate extension 92. A stop-screw is threaded through lug 88 and adapted to engage lug 91. Also a stop-screw is threaded through plate-extension 92 and adapted to engage finger 89.

The shaft 71 of each switch unit carries an arm 93, the free end of which is adapted to engage upon the plate extension 92, as shown in Figure 4.

Previous to the use of the apparatus heretofore described the tank 27 should be filled with mercury to the level of the first exposed lower end of conductors 18. Also the tanks 40 and 41 are partly filled with water and partly with oil of high electrical resistance. The oil should also fill the chambers 29 and 30 and their associated bores 31 and 32, respectively. The tank 11 is partly filled with water and then air pressure admitted equal to

the operating steam pressure of a boiler. It is to be understood that a control apparatus as heretofore described is provided for each boiler controlled, and thus the outlets from pressure tank 11 will correspond to the number of boilers or furnaces being controlled. With the above conditions present, the proper valves are opened for bringing the pressure tank 11 into communication with the lower end of tank 41. Also the proper valves are opened for bringing the lower end of tank 40 in communication with the high pressure side of steam main 10 and the lower end of tank 15 in communication with the low pressure side of steam main 10. The high pressure side and low pressure side of steam main 10 exist on opposite sides of the orifice plate 44 as previously explained. Assuming the rate of steam flow in main 10 is such that the differential pressure across orifice plate 44 causes mercury in receptacle or tank 27 to rise to a point to cover the lower terminals of a number of conductors 18, and that the contact fingers 63 and 64 are disposed upon contacts 59 connected to the conductors 18 having their lower ends covered by mercury, then an electrical circuit is established through each of the electro-magnets 70' and 71' and the switch unit 70^a is opened while switch unit 69^c is closed. This results in rotating the motor 14 for imparting rotation to shaft 58 in a clockwise direction, and such rotation is continued until finger 64 has contact with one of the segment contacts that are connected to conductors 18 not contacting with mercury in tank 27. Switch 69^c then opens and motor remains stationary until change in level of mercury is effected. This rotation of the wheel 13 can be utilized in an obvious manner for increasing the fire beneath a boiler through one of the bell-crank levers 66-67. When the fingers 63-64 leave contacts 59 and which not capable of establishing a circuit through magnets 70' and 71' then switch unit 70^a will open and switch 69^c close and thus reverse the direction of rotation of motor 14. The wheel 13 will now be rotated counter-clockwise until the fingers 63-64 reach contacts 59 that are connected with conductors 18 having their lower and exposed ends in contact with mercury within tank 15, at which time the direction of rotation of the motor 14 is stopped and rotated in a clockwise direction in an obvious manner. This rotation of the shaft 58 and attached cams 64 and 65 can be utilized in an obvious manner for increasing the fire beneath a boiler through one of the guide links 66-67 and their connecting rods. When the level of mercury is lowered causing break in circuit through contact finger 63, switch 60 is closed by springs 77 causing motor to rotate shaft 56 in counterclockwise direction until finger 63 contacts segment 59 whose conductor 18 is immersed in mercury, thus open-

ing switch 69^c. Motor will now remain stationary until change in level of mercury occurs. It will thus be seen that each change in demand for steam will change level of mercury and cause motor and shaft 56 to rotate thus increasing or decreasing rate of combustion to meet new conditions. 76

The operation heretofore described would permit each boiler controlled from the pressure tank 11 to assume its portion of load 75 at all times. If it is desired that one boiler lead others in a group, that is, take more load than the others, the same may be accomplished by raising the mercury cup 27 through hand wheel 26. Also the same purpose may be accomplished by loosening clamp 61 and rotating wheel 13 clockwise to increase combustion under the controlled boiler or counter-clockwise for decreasing combustion. 80

If it should be desired to operate a boiler at a fixed load, valves 49 and 47' are closed and valves 54 and 55^a opened thereby connecting chamber 29 with low pressure side of steam main and tank 15 with high pressure side of steam main. The mercury tank is now raised by hand wheel 26 until the proper regulation of the associated furnace is obtained for carrying a certain load. Under this condition any rise in steam pressure will cause rotation of shaft 56 to reduce such pressure counterclockwise as viewed in Fig. 1 and any lowering of steam pressure in steam main will bring about reverse rotation of shaft 56, thus increasing rate of combustion. 90

An increase in steam flow above that for which furnace control is set will increase difference in pressure between inlet and outlet sides of orifice plate depressing mercury in tank 27 thus causing rotation of shaft counterclockwise to decrease rate of combustion. 105

While I have shown and described the preferred form of my invention as well as the preferred combination and arrangement of parts constituting the same, I wish it to be 110 understood I am not to be so limited as indicated by the appended claims.

I claim:—

1. In combination a steam main subject to changes of steam pressure therein, a constant fluid pressure, connections between the steam main and constant fluid pressure, including pressure tanks filled with fluids, and means whereby the fluids will establish electrical control circuits when the pressure in the 115 steam main varies from the fluid pressure. 120

2. In combination a steam main subject to changes of steam pressure therein, a constant fluid pressure, connections between the steam main and constant fluid pressure, pressure tanks interposed in said connections including a container having mercury therein adapted to rise and drop in said container with change in pressure of steam main with respect to fluid pressure, and means where- 125 130

by electrical control circuits are established with change of level of mercury.

3. In combination a steam main subject to changes of steam pressure therein, a constant fluid pressure, connections between the steam main and constant fluid pressure, pressure tanks interposed in said connections including a container having mercury therein adapted to rise and drop in said container with change in pressure of steam main with respect to fluid pressure, a plurality of conductors within the container arranged for establishing different electrical control circuits with change of level of said mercury.

4. In combination a steam main subject to changes of steam pressure therein, a constant fluid pressure, connections between the steam main and constant fluid pressure, pressure tanks interposed in said connections including a container having mercury therein adapted to rise and drop in said container with change in pressure of steam main with respect to fluid pressure, a plurality of conductor wires within the container having terminals exposed to the mercury when at different levels, and means whereby each conductor will establish an electrical circuit when contacting with the mercury.

5. In combination a steam main subject to changes of steam pressure therein, a constant fluid pressure, connections between the steam main and constant fluid pressure, pressure tanks interposed in said connections including a container having mercury therein adapted to rise and drop in said container with change in pressure of steam main with respect to fluid pressure, means whereby electrical control circuits are established with change of level of mercury, and means whereby said circuits are utilized for providing mechanical motions.

6. In combination a steam main having an orifice plate therein to provide high and low pressures on opposite sides thereof, a constant pressure fluid source, fluid pressure tanks and connections between the constant pressure fluid source and the high and low pressure sides of the steam main, and means associated therewith whereby electrical control circuits will be established when the pressures in said steam main vary from a predetermined relation to the constant fluid pressure.

7. In a furnace control, a steam main having an orifice plate to provide high and low pressure on opposite sides thereof, a constant pressure fluid source, a pair of tubular pressure tanks one of which is connected to the constant fluid pressure tank and the other of which is connected to the low and high pressure sides of the steam main, a mercury column positioned between and responsive to the fluid pressure in said tanks and unitary control means responsive to the movement of said mercury for controlling the furnace.

8. In a furnace control apparatus, a steam main having an orifice plate providing high and low pressure on opposite sides thereof, an automatic switch control means having three tubular fluid pressure chambers connected to the high and low pressure portions of a steam main and a constant fluid pressure tank respectively, a tubular column of mercury situated between said high pressure tubular chamber, said constant pressure tubular chamber and said low pressure tubular chamber and responsive to the pressure therein and unitary electrically controlled means responsive to the movement of said mercury for controlling the furnace.

9. In a furnace control apparatus, a mercury switch comprising three tubular chambers connected to the high and low pressure portions of a steam main and a constant pressure tank respectively, a column of mercury therein, adapted to respond to the pressure in the low pressure tubular chamber on one side thereof and the pressure in the high pressure tubular chamber and the constant pressure tubular chamber on the opposite side thereof, and unitary control means responsive to the movement of said mercury to control the furnace.

10. In combination, a steam main subject to changes of steam pressure therein, a constant fluid pressure source, connections between the steam main and constant fluid pressure, pressure tanks interposed in said connections including a container having mercury therein adapted to rise and drop in said container with change in pressure of said steam main with respect to fluid pressure, a plurality of conductors within the container, an electric motor, a control unit therefor, electrical circuits between said control unit and said conductors for rotating said motor in clockwise and counterclockwise directions with change of level of said mercury.
